(57) **CLAIM**

The ornamental design for a sex toy, as shown and described.

DESCRIPTION

FIG. 1 is a front perspective view of embodiment 1, showing my new design;

FIG. 2 is a bottom perspective view of embodiment 1;

FIG. 3 is a front view of embodiment 1;

FIG. 4 is a rear view of embodiment 1;

FIG. 5 is a left side view of embodiment 1;

FIG. 6 is a right side view of embodiment 1;

FIG. 7 is a top view of embodiment 1;

FIG. 8 is a bottom view of embodiment 1;

FIG. 9 is an enlarged detail view of area 9 in FIG. 1;

FIG. 10 is a front perspective view of embodiment 2;

FIG. 11 is a bottom perspective view of embodiment 2;

FIG. 12 is a front view of embodiment 2;

FIG. 13 is a rear view of embodiment 2;

FIG. 14 is a left side view of embodiment 2;

FIG. 15 is a right side view of embodiment 2;

FIG. 16 is a top view of embodiment 2;

FIG. 17 is a bottom view of embodiment 2; and,

FIG. 18 is an enlarged detail view of area 18 in FIG. 10.

The dash-dot-dash broken lines encircling the enlarged views are for annotative purposes only and form no part of the claim thereof.
